TRAURIG LLP(57) CLAIM

The ornamental design for a bank check as shown and described.

DESCRIPTION

FIG. 1 is a front elevational view of a bank check showing our new design according to a first embodiment.

FIG. 2 is a front elevational view of a second embodiment of the bank check;

FIG. 3 is a front elevational view of a third embodiment of the bank check;

FIG. 4 is a front elevational view of a fourth embodiment of the bank check;

FIG. 5 is a front elevational view of a fifth embodiment of the bank check;

FIG. 6 is a front elevational view of a sixth embodiment of the bank check; and,

FIG. 7 is a front elevational view of a seventh embodiment of the bank check.

The broken lines are for illustrative purposes only and form no part of the claimed design.
